The new Haarslev Fat Screw Press FSP3500, announced in YouTube on Feb. 15, 2022 [online], [site visited May 25, 2023], Available from the internet URL:<https://www.youtube.com/watch?v=yDZ7H65GYEI> (Year: 2022).*

Primary Examiner — Calvin E Vansant*Assistant Examiner* — Eidiol Ghigliotti Torres(74) *Attorney, Agent, or Firm* — Nath, Goldberg & Meyer; Jerald L. Meyer; Morgan D. Rosenberg(57) **CLAIM**

The ornamental design for an engine for fat screw press, as shown and described.

DESCRIPTION

FIG. 1 is the perspective view of the engine for fat screw press;

FIG. 2 is the front view thereof;

FIG. 3 is the rear view thereof;

FIG. 4 is the left side view thereof;

FIG. 5 is the right side view thereof;

FIG. 6 is the top plan view thereof; and,

FIG. 7 is the bottom plan view thereof.

The broken lines in the drawings are for the purpose of illustrating portions of the engine for fat screw press that form no part of the claimed design.

1 Claim, 7 Drawing Sheets(56)
